Application July 27, 1935, Serial No. 57,825

Term of patent 3½ years

To all whom it may concern:

Be it known that I, Henry Kraus, a citizen of the United States of America, residing at Mount Vernon, Westchester County, State of New York, have invented a new, original, and ornamental Design for a Window-Curtain Ensemble, of which the following is a specification, reference being had to the accompanying drawing, forming part thereof, in which the figure is a perspective view of a window-curtain ensemble showing my new design.

The bottom draperies are an integral part of

the unit. The essential feature of the design is the combined ensemble of the drapes and the canopy, the canopy overhanging to a substantial extent the drapery and the top of the canopy being inclined downwardly, having a downward panel or extension.

I claim:

The ornamental design for a window-curtain ensemble, substantially as shown and described.

Signed at New York city, this 26th day of July, 1935.

HENRY KRAUS.
